UNITED STATES PATENT OFFICE.

CHARLES EDWARD SULLIVAN, OF MILL CITY, OREGON.

LOGGING BUTT-HOOK.

1,161,751.

Specification of Letters Patent. Patented Nov. 23, 1915.

Application filed September 25, 1913. Serial No. 791,877.

To all whom it may concern:

Be it known that I, CHARLES E. SULLIVAN, a citizen of the United States, residing at Mill City, in the county of Marion and State of Oregon, have invented certain new and useful Improvements in Logging Butt-Hooks, of which the following is a specification, reference being had therein to the accompanying drawing.

This invention relates to hooks and particularly to that kind employed in logging known as butt-hooks for use on the end of a cable used by lumbermen in hauling logs.

The object of this invention is to provide a hook of the kind above described that is strong, durable and which will firmly engage the chain or other object to which it is connected.

Another object of this invention is to provide an improved means for holding the hook proper in a locked or closed position when the same is in engagement with a chain or other object.

With these and other objects in view this invention consists of certain novel combinations, constructions and arrangements of parts as will be hereinafter fully described and claimed.

In the accompanying drawing: Figure 1 is a perspective view of the improved hook. Fig. 2 is a side elevation of the hook with one of the side plates broken away and the eye shown in section.

Referring to the parts by reference numerals 10 designates the side plates of the housing which have positioned between them the spacing block 11, said plates and block are held together by the rivets 12. Formed in the block 11 is a longitudinally extending slot 13 having an enlarged outer end portion 14 which has a cut-out portion 15 forming the shoulder 16 leading therefrom. It will be seen that the slot 13 formed in the block 11 constitutes a pocket or recess when the device is assembled by means of the side plates 10. A longitudinally extending bore 17 is formed in the block 11 at the opposite end to that of the enlarged opening 14 and communicates with the slot 13.

Positioned in the bore 17 and extending through the pocket or recess formed by the slot 13 and the enlarged opening 14 is a plunger rod 18 having a head 19 on one end, said head 19 adapted to be positioned in the notch 20 of the block 11 to limit the

movement of the plunger rod. A latch member 21 is secured to the opposite end of the plunger rod from that of the limiting head 19. Wound around the plunger rod 20 is a coil spring 22 which has one end resting on the bottom of the slot 13 and the other end positioned against the under or inner face of the latch member 21 so as to normally hold the latch in a position as shown in Fig. 2.

The hook proper is pivotally mounted between the side plates 10 by means of the pin 23. The securing eye 24 is also pivotally mounted to the housing by means of the pin 23. The hook proper 25 has the usual bill 26 the end of which is adapted to be positioned between the shoulder 16 and the latch member 21 when in a locked position. A cut-out or finger inserting portion 27 is provided in one of the side plates 10 to provide means for the depression or unlocking of the latch member 21.

It will be seen from the foregoing description that the chain or cable is attached to the eye 24 and the hook proper 25 passes around the choke line of a log and the bill is positioned as shown in Fig. 2, and, of course, the same can not be withdrawn until the latch member 21 is depressed. Although this invention has been described and especially designed for use in lumbering and is generally known as the butt-hook, the improvement may be embodied in other kinds of hooks particularly those of the general class of snap-hooks.

It is obvious that minor changes may be made in the form and construction of this invention without departing from the spirit thereof. It is therefore not wished to confine the invention to the exact form herein shown and described, but it is wished to include all such as properly come within the scope claimed.

Having thus described the invention, what is claimed as new, is:

As a new article of manufacture a logging butt hook comprising a block, said block provided with a centrally located pocket, a plunger carried by said block, a spring mounted upon said plunger, a latch member carried by the outer end of said plunger, a hook pivotally secured to said block and provided with an inwardly extending bill, said block provided with a bill receiving cut out portion, said body pro-

vided with a cut out finger receiving portion upon one side thereof for permitting said latch member to be pushed inwardly in order that said hook may be swung outwardly and said inwardly extending bill being adapted to overhang said latch member and prevent said hook from being swung outwardly until said latch member has been

pushed inwardly beyond the outer edge of said block.

In testimony whereof I hereunto affix my signature in presence of two witnesses.

CHARLES EDWARD SULLIVAN.
